ELECTRICALLY CONTROLLED PUMP MOTOR

Toby B. Harper, Tulsa, Okla.

Application June 4, 1952, Serial No. 291,635

4 Claims. (Cl. 318—482)

This invention relates to an apparatus for controlling the operation of a motor for pumping fluid from a well and more particularly to apparatus for controlling operation of a motor for pumping fluid from a well between two defined fluid levels in the well.

It has been the practice in pumping wells such as oil wells which are not considered to be very good producers to pump according to a certain time schedule. This scheme is designed to prevent losing the prime on the pump. The time schedule adopted is arrived at by experience alone and is often incorrect, in which case the prime is sometimes lost. This necessitates effort and delay which is often very costly.

It is therefore an object of this invention to regulate the operation of the pump automatically to prevent any possibility of loss of prime.

Broadly speaking, this object is accomplished by employing a series of switches including float switches located in the well. These float switches sense the level of the fluid and determine when the pumps should or should not operate. They insure that the pump will operate only when the level of the fluid is enough to provide suitable prime for the pump.

These and other objects will become apparent from a detailed description of the accompanying drawings.

Figure 1 is a figure partly in section and partly diagrammatic showing a cased well including the tubing and the pump motor, and also including the control circuit for the pump motor;

Figure 2 is a view partly in section of one of the float switches which is in accordance with this invention; and

Figure 3 is another view partly in section of the float switch of Figure 2.

Referring to Figure 1, numeral 10 indicates the casing which is sunk into the earth. Numeral 11 indicates the tubing which provides the necessary conduit for the removal of the fluid. A sucker rod 12, having a valve head 13 is positioned in the tubing 11. At the bottom of the tubing is a valve 14 which is, in the usual case, a check valve. The fluid is removed in the usual manner by forcing the sucker rod downwardly. The fluid which has entered the tubing through the check valve 14 which is open during the upstroke passes through the valve head 13 and the check valve 14 is closed. On the upstroke the fluid is carried upwardly, the check valve 14 opens and more fluid is admitted to the tubing.

Float switch 15 is located in the well a predetermined distance above the bottom of the hole. Float switch 16 is located in the well a predetermined distance above switch 15. The distance between these two switches determines the levels between which the pump is to operate.

Turning to Figures 2 and 3, each float switch is comprised of a bulb 17 which may be of hollow glass and sealed liquid-tight. A tubular container 18 is formed integral with the bulb 17 but sealed off from said bulb. 19. A cap 20 seals the container 18 from the outside. Electrical terminals 21 and 22 are provided within the container 18 and wire leads 23 and 24 engage these terminals within this container. These terminals are spaced one from the other and are partly insulated at 25 and 26.

A clamp 27 fits about the cable 28 and is held in position by bolt and nut assembly 29. To this clamp the float switch is pivotally mounted by means 30. It can be seen that with the bulb in unfloated position such as in Figure

2

2, the globule of mercury is at the right hand end of the tubular container 18. When the fluid buoys the bulb 17 upwardly, the globule moves to the left and immerses the exposed portions of the terminals 21 and 22 to thereby close the switch, that is to provide a complete circuit between the leads 23 and 24. Both switches 15 and 16 are such as is shown in Figures 2 and 3. They are mounted to cable 28 which carries the wire connectors from the motor control circuit located at the top of the hole.

Turning back, now, to Figure 1, let us examine the motor control circuit for the pump. The motor 29 may be of any conventional type with the usual connection between drive shaft and sucker rod. A power supply supplies power to posts 30 and 31. Tracing the side of the power supply arriving at post 31, it passes through wire connector 32 into the cable 28 and downwardly to one of the electrical terminals in switch 16 and also to one of the electrical terminals in switch 15. Tracing the other side of the power supply from post 30, it is seen that it goes through connector 33 to one side of the motor and through wire connector 34 to one side of a solenoid 35. The other side of the solenoid leads through wire connector 36 to one side of a spring-biased microswitch 37. Wire connector 38 leads from the same side of this microswitch back to the other side of the motor. From the same side of the solenoid 35, wire connector 39 leads into the cable 28 downwardly to the other electrical terminal of float switch 16. The wire connector 40 from the microswitch 37 leads into the cable 28 and downwardly to the other electrical terminal of the switch 15. The microswitch is biased to a normally open position by a leaf spring 41 and held in tension by coil spring 42 which is mounted at one end to brace 43 which supports the microswitch and at the other end to arm 44 which is connected to the topmost terminal of the switch 45 and pivoted at 46 to the brace 43.

Following the side of the power supply to the motor which arrives at post 30, we see that it passes through wire connector 34 to solenoid 35. The other side of the solenoid 35 passes through wire connector 39 through switch 15 to the other side of the power supply which arrives at post 31. It can be seen, then, that the solenoid will not be energized through this path unless switch 16 is closed. Therefore the microswitch which is operated by the solenoid 35 will not operate unless float switch 16 is closed. Therefore, as the fluid level in the tubing rises it first closes float switch 15. With float switch 15 closed, of course the solenoid still has no complete path. The fluid level continues to rise and finally closes float switch 16. At this time the solenoid is energized because it has a complete path from post 30 to post 31 through wire connector 34, wire connector 39, the switch 16, and wire connector 32. At this point the microswitch 37 closes and therefore the motor 29 commences to operate. As the liquid level falls below the level of float switch 16, the solenoid will still remain energized and the mercury switch 37 still closed because the solenoid has a complete path from terminal 30 through wire connector 34, wire connector 36, the switch 37, wire connector 40, float switch 15 and wire connector 32. However, when the liquid level drops below float switch 15, this last remaining path for the solenoid 35 is broken and the solenoid is de-energized, microswitch 37 opened and the motor stopped. This then allows the fluid to regain its level without the motor operating and the cycle is again repeated.

It can be seen, then, that the motor will not be energized until both of the float switches are floated initially and will continue to operate when the topmost float switch, that is switch 16, is no longer floated but while float switch 15 is still being floated, and will stop operating when both float switches are no longer buoyed up by the fluid in the well. This gives close control of the time during which the motor will operate and assures that the motor will not operate unless there is sufficient head to provide a good prime for the pump. The levels of the two switches are so adjusted that a good head for priming purposes will be maintained.

What has been disclosed is a specific embodiment of the present invention. Other embodiments obvious from the teachings herein to those skilled in the art are con-

3

templated to be within the spirit and scope of the following claims.

What is claimed is:

1. Apparatus for controlling the operation of a motor for pumping fluid from a well that comprises a power supply for said motor, one side of said power supply being connected directly to one side of said motor, the other side of said power supply being connected to the other side of said motor through two paths, one path including in series a first float switch positioned in said well and a solenoid-operated switch, the other path including in series a second float switch positioned above said first float switch in said well and a solenoid to operate said solenoid-operated switch. 15

2. Apparatus as defined by claim 1 wherein said float

switches are open when unfloated.

3. Apparatus as defined by claim 2 wherein said float switches are mercury switches.

4. Apparatus for controlling the operation of a motor for pumping fluid from a well that comprises a power supply for said motor, one side of said power supply being connected directly to one side of said motor, the 20

other side of said power supply being connected to the other side of said motor through two paths, one path including in series a first float switch positioned in said well and a solenoid-operated switch, the other path including in series a second float switch positioned above said first float switch in said well and a solenoid to operate said solenoid-operated switch, whereby when the fluid level in said well rises above said first float switch, said first float switch closes and when said fluid level rises above said second float switch, said second float switch closes to energize said solenoid and close said solenoid-operated switch to energize said motor and when said fluid falls below the level of both of said switches said motor is de-energized.
